WINDOW SEAT

Joseph A. Costello, Cleveland, Ohio; Thomas A. Costello, executor of said Joseph A. Costello, deceased, assignor to Thomas A. Costello

Application April 21, 1934, Serial No. 721,720

12 Claims. (Cl. 304—24)

This invention relates to an improved form of seat which can be placed upon the window sill of a house or other building so as to facilitate the washing of the window upon the outside thereof. 5 This application is a continuation in part of my application, Ser. No. 705,002, filed January 2, 1934, Patent 2,004,237.

As stated in my companion application, there have been devised various forms of window seats 10 for this general purpose and there have been granted a number of patents thereon but they are all rather complicated in structure and inconvenient in operation and therefore impractical from the standpoint of marketable merchandise.

15 In the present case, as well as in my companion application, the entire body of the window seat consists of a single, one-piece body of sheet metal which is integrally formed with means of interengagement about the window sill for maintaining the same in proper position and which is provided also with an adjustable means for adapting the seat for use upon window sills of different types and dimensions.

Whereas in my companion application the window seat is adapted for use upon window sills which are of plain angular form upon the inside thereof, the object of the present invention is to devise a window seat which may be adjusted so as to adapt it for use either upon the form of window sill just referred to or upon another familiar form of window sill which comprises a molding upon the under-side of the inner part thereof.

30 More specifically, the object of the present invention is to devise a window seat which consists of an integral body throughout the entire extent thereof and which can be readily adjusted and then securely fixed in such adjustment for use upon either of the several forms of window sills above referred to.

40 Another object of the present invention consists in devising such a window seat that may be readily applied to and removed from the window sill while at the same time, there is provided means for preventing the seat from marring the finish of the window sill.

Other objects will appear from the following description and claims when considered together with the accompanying drawing.

50 Fig. 1 is a plan view of my present improved form of window seat;

Fig. 2 is a side elevation thereof showing the same applied to the form of window sill in which a strip of molding is provided beneath the inner 55 part of the window sill;

Figs. 3 and 4 are sectional views taken on lines 3—3 and 4—4, respectively, of Fig. 1;

Fig. 5 is a partial view similar to Fig. 2 and shows how my present improved form of window seat may be applied to the other form of window sill having substantially rectangular form upon the inner side thereof; and

Fig. 6 is a view similar to Fig. 5 and shows the application of the present window seat to a window sill of the same form as that illustrated in Fig. 5, but of greater extent.

As in my companion application above referred to, so also in the present form of window seat, the entire body of the seat is pressed out of sheet metal and has an upturned wall 1 for more comfortably and securely supporting the body of the user. The edge portion of the wall 1 is formed with the flange 2 for the purpose of reinforcement.

While the main outer part of the window seat assumes a downwardly and outwardly inclined position when applied to the window sill, as clearly indicated in Fig. 2, it will be observed that that part of the window seat which extends inwardly between the window sill occupies substantially horizontal position.

The inner part of the seat comprises the lower portion 4 which is substantially parallel with the upper horizontal portion 3 and which is joined thereto by means of the intermediate integral bowed portion 5. The lower portion 4 has its edge portions flanged downwardly, as indicated by reference numeral 6, for the purpose of reinforcement and there is provided also the transversely extending rib 7 at approximately the line of juncture between the lower portion 4 and the intermediate portion 5.

It will be observed that the intermediate portion 5 is of plain form and by choosing metal of suitable character and gauge, the intermediate portion 5 may serve as a connecting hinge portion, the bending action of which is limited to the extent of the bowed portion itself. Because of the reinforcing flanges of the upper part 3 and also the reinforcing means provided for the lower portion 4, any bending of the middle portion 5 will be confined to the extent thereof and there will not be permitted any bending of the portions beyond the same.

The upper part 3 is provided with the slots 8 while the lower part 4 is provided with the slots 50 9, the upper and lower slots in each case overlapping each other, as indicated in Fig. 1. These slots accommodate the threaded bolts 10 which extend therethrough and which are adapted to engage the upper and lower parts 3 and 4. The 55

wing nut 11 is provided upon the bolt 10 for engagement of the under side of the part 3 while the wing nut 12 is provided upon the bolt 10 for the engagement of the under side part 4. The 5 head of the bolt engages the upper side of the part 3 while the nut 13 is provided upon the bolt 10 for engaging the upper side of the part 4. Suitable washers are provided between the head of the bolt and the nuts.

10 Briefly, the bolt 10 upon loosening the nuts, may be set in the proper position after suitably bending the intermediate part 5 and the bolt 10 may then be locked in such adjusted position preliminary to applying the window seat to the sill of a given window. This will be more fully explained 15 below.

The bottom part of the seat is provided with an integrally downwardly extending rib 14 which extends partially across the same and in the middle part thereof. This rib or foot is adapted to rest upon the drain strip B at a point just outside of the sill strip A. The bolts 10 are preliminarily set for any given window sill so that the rib 14 will in all cases occupy the position just referred to. In this way, the seat has a means of interengagement with the inner and outer edges of the sill strip A by virtue of the location of the bolts 10 and rib 14, respectively. This will more fully appear in the explanation below.

30 The outer part of the seat is adapted to rest upon the drain strip B, as indicated in Fig. 2, and the rib 14 is of such depth that there is allowed a clearance between the sill strip A and the upper part of the seat. One advantage served by this arrangement is that there is avoided the danger of marring the paint or other finish upon the top surface of the sill strip A; and as a further means toward this end, there is provided the rubber member 15 which is secured to the under side of the seat in the depressed portion 16 which extends partially and longitudinally through the middle part of the seat, as indicated in the drawing.

45 As a further means toward preventing marring of the outer top corner portion of the sill strip A, I have provided the integrally formed, transversely extending rib 17 which is so positioned that it may engage the outer upright side of the sill strip in case the seat should be moved and in this way the danger of the seat engaging and 50 marring the edge of the sill strip is prevented.

55 Between the rib 14 and the outer bottom part of the seat, I have provided a raised portion 18 to accommodate the weather-stripping, this portion 18 being of sufficient extent in a direction from the inside toward the outside to accommodate the different locations of weather-stripping for different sizes of windows. This raised portion 18 is so graduated in its contour upon the outer side thereof that it conforms to the general 60 form of the seat bottom and does not interfere with the comfortable seating of the user.

65 The main body of the seat is provided with another integral rib or foot 19 which is adapted to rest upon the wall D of a brick or stone house and thereby afford further support for the outer part of the seat. When the seat is employed in connection with a frame house, the rib 19 will extend just outside of the drain strip B so as not to interfere with the main body of the seat resting upon the drain strip. Upon the bolt 10, I have 70 provided the rubber ring member 20 which is adapted to prevent any marring of the inner part of the weather strip A.

75 It will be observed that when my window seat is employed in connection with a window sill of

the type indicated in Fig. 2, the lower part 4 will occupy a comparatively rearward position which is permitted by the nature of the intermediate portion 5. That is, the lower part 4 may be moved rearwardly with respect to the top part 3 while the intermediate portion 5 serves as a hinge connection. Thus, it will be noted that in Fig. 2 the intermediate or bowed portion 5 has a different curvature from that indicated in Figs. 5 and 6. As above explained, this adjustment may 10 be accomplished by loosening the wing nuts 11 and 12, then adjusting the lower part 4 to the desired position, then setting the bolt 10 at the position desired with respect to the rear edge of the window sill, and then finally tightening the 15 nuts 11 and 12 so as to maintain the bolt 10 in such position. It should be explained that the nut 13 occupies proper position on the bolt 10 so that when the single nut 12 is tightened, the lower part 4 will occupy substantially parallel re- 20 lation with the upper part 3.

Then should it be desired at any time to employ the window seat in connection with a window sill of the type indicated in Fig. 5, the lower part 4 may be moved forwardly by first loosening the 25 nuts 11 and 12 and bending the intermediate portion 5 and finally setting the bolt 10 and locking it in such position by tightening the wing nuts 11 and 12.

30 In case the window seat should be applied to a window sill of greater depth, as illustrated for instance in Fig. 6, it might be desirable to adjust the lower part 4 forwardly even to a still greater degree than required for the window sill illustrated in Fig. 5. If so, this may be accomplished in 35 the same manner as already described.

40 Thus, in all cases, it will be seen that with my form of device, the lower part 4 and the bolt 10 associated therewith are set in the proper position with respect to the particular type of window sill upon which the seat is to be employed and then the seat is actually applied to the window sill by first engaging the inner part thereof about the inner edge of the window sill while holding the seat in inclined position and lowering the main 45 body of the window seat in a downward and outward movement so as to occupy the position indicated in the drawing. No manipulation or adjustment is required after the window seat has been placed in such position.

50 The clearance between the rear or inner part of the seat and the sill strip, permits the seat to be applied in the manner just explained and in this way the rib 14 is brought into position just in front of the sill strip.

55 In order to remove the seat from the window sill, the reverse manipulation is followed. That is, the outer part of the seat is turned upwardly and inwardly while at the same time the seat is moved backwardly so as to remove the inner part thereof 60 from engagement with the sill strip.

65 It will be observed that when the window seat has been placed in position, it is virtually locked in such position so as not to become accidentally dislodged either forwardly or rearwardly since the bolt 10 together with the lower part 4 will prevent any substantial forward movement while the foot or rib 14 will prevent any accidental dislodgment inwardly. That portion of the lower part 4 which extends in under the window sill will 70 also prevent any upwardly tilting movement of the inner part of the window seat.

75 In the manufacture of my window seat, it is pressed from a single piece of sheet metal, all parts thereof being formed by the same single opera- 75

tion, except for bending the rear part thereof so as to provide the underlying parallel portion 4 and except for the familiar trimming of the edge. A suitable gauge of sheet metal is employed to afford the strip required and to permit the bending action of the intermediate bowed portion 5.

Although my seat is formed from a single sheet of metal, yet it is sufficiently reinforced by means of the several ribs and flanges already referred to and furthermore, the parallel portions 3 and 4 are braced by means of the bolts 10.

Thus, I have devised a comparatively inexpensive form of window seat which is of comparatively simple construction and which can therefore be manufactured and sold at a comparatively low price while at the same time it can be conveniently adjusted and applied to any one of several forms of window sills. Furthermore, this window seat possesses a high degree of safety and there is nothing to adjust or to get out of order after once it has been set for a given window sill.

What I claim is:

1. A window seat comprising a main portion adapted to extend across the window sill and to support the body of the user, and an inner portion adapted to extend about and beneath the inner edge of the window sill and having a flexible intermediate portion adapted to extend about the rear edge of the seat, said inner portion being hingedly connected by means of said intermediate portion with said main portion so as to permit adjustment of the inner portion forwardly or rearwardly with respect to the main portion, and adjustable means for co-operating with said inner portion in establishing and maintaining the effective position thereof for window sills of different dimensions.

2. A window seat comprising a main portion adapted to extend across the window sill and to support the body of the user, and an inner portion adapted to extend about and beneath the inner edge of the window sill and having a flexible intermediate portion adapted to extend about the rear edge of the seat, said inner portion being hingedly connected by means of said intermediate portion with said main portion so as to permit adjustment of the inner portion forwardly or rearwardly with respect to the main portion, and adjustable means extending between said main and inner portions for co-operation with said inner portion in establishing and maintaining the effective position thereof for window sills of different dimensions.

3. A window seat comprising a main portion adapted to extend across the window sill and to support the body of the user, and an inner portion adapted to extend about the inner edge of the window sill, said inner portion being integrally and hingedly connected with said main portion so as to permit adjustment of the inner portion forwardly or rearwardly with respect to the main portion, and adjustable means extending between said main and inner portions for co-operation with said inner portion in establishing and maintaining the effective position thereof for window sills of different dimensions.

4. A window seat comprising a main portion adapted to extend across the window sill and to support the body of the user, and an inner portion adapted to extend about the inner edge of the window sill, said inner portion being integrally and hingedly connected with said main portion by means of a bowed portion so as to permit adjustment of the inner portion forwardly or rearwardly

with respect to the main portion, and adjustable means for co-operating with said inner portion in establishing and maintaining the effective position thereof for window sills of different dimensions.

5. A window seat comprising a main portion adapted to extend across the window sill and to support the body of the user, and an inner downwardly-and-forwardly turned portion adapted to extend about the inner edge of the window sill 10 and being integrally and hingedly connected with said main portion by means of a bowed portion so as to permit adjustment of the inner portion forwardly or rearwardly with respect to the main portion, and adjustable means extending between 15 said main and inner portions for co-operation with said inner portion in establishing and maintaining the effective position thereof for window sills of different dimensions.

6. A window seat comprising a main portion 20 adapted to extend across the window sill and to support the body of the user, and an inner downwardly-and-forwardly turned portion adapted to extend about the inner edge of the window sill and comprising a lower portion substantially parallel with that part of the main portion thereabove and comprising also a bowed portion integrally and hingedly joining the lower portion with the main portion so as to permit adjustment of the inner portion forwardly or rearwardly with 30 respect to the main portion, and adjustable means extending between said main and inner portions for co-operation with said inner portion in establishing and maintaining the effective position thereof for window sills of different dimensions. 35

7. A window seat comprising a rigid main portion adapted to extend across the window sill and to support the body of the user, and an inner downwardly-and-forwardly turned portion adapted to extend about the inner edge of the window 40 sill and comprising a lower rigid portion substantially parallel with that part of the rigid main portion thereabove and comprising also a bendable bowed portion integrally and hingedly joining the lower rigid portion with the main rigid portion 45 so as to permit adjustment of the inner portion forwardly or rearwardly with respect to the main portion, and adjustable means extending between said main and inner portions for co-operation with said inner portion in establishing and maintaining the effective position 50 thereof for window sills of different dimensions.

8. A window seat comprising a main portion adapted to extend across the window sill and to support the body of the user, and an inner portion adapted to extend about the inner edge of the window sill, said inner portion being integrally and hingedly connected with said main portion so as to permit adjustment of the inner portion forwardly or rearwardly with respect to 55 the main portion, and adjustable bolt means extending between said main and inner portions for co-operation with said inner portion for establishing and maintaining the effective position thereof for window sills of different dimensions. 60

9. A window seat comprising a main portion adapted to extend across the window sill and to support the body of the user, and an inner downwardly-and-forwardly turned portion including 70 a flexible intermediate portion adapted to be freely engageable about the inner edge of the window sill, said portions being relatively adjustable by means of said intermediate portion, adjustable means for cooperating with said inner 75

portion in establishing and maintaining the effective position thereof for window sills of different dimensions and means provided in said main portion of the seat at a point outside the inner 5 part of the window sill and adapted for supporting engagement upon the outer part of the window sill, said supporting means being of sufficient height and being so formed as to provide clearance for the weather-stripping and being provided with means adapted to prevent scarring of the front corner portion of the window sill, and means provided upon the under side of the seat for preventing scarring of the top and inner surface portions of the window sill, said parts being 10 15 so constructed and arranged that the seat may be first adjusted and then applied to the window sill by first applying the inner portion of the seat to the inner edge of the window sill and then lowering the seat into supported position upon the outer part of the window sill without interference 20 25 by the inner part thereof or by the weather-stripping and without marring the window sill.

10. A window seat comprising a main rigid portion adapted to extend across the window sill and to support the body of the user, and an inner downwardly-and-forwardly turned portion adapted 25 30 to extend about the inner edge of the window sill and comprising a lower rigid portion substantially parallel with that part of the main rigid portion thereabove and comprising also a bendable bowed portion integrally and hingedly joining the lower rigid portion with the main rigid portion so as to permit adjustment of the inner portion forwardly or rearwardly with respect to the main portion, said parallel upper and lower rigid portions being provided with overlapping slots extending forwardly and rearwardly, substantially vertically disposed bolt means extending through said slots, and releasable means for 35 40 securing said bolt means in adjusted position so that the bolt means may co-operate with the inner portion for establishing and maintaining

the effective position thereof for window sills of different dimensions.

11. A window seat comprising a main rigid portion adapted to extend across the window sill and to support the body of the user, and an inner downwardly-and-forwardly turned portion adapted 5 to extend about the inner edge of the window sill and comprising a lower rigid portion substantially parallel with that part of the main rigid portion thereabove and comprising also a bendable bowed portion integrally and hingedly joining the lower rigid portion with the main rigid portion so as to permit adjustment of the inner portion forwardly or rearwardly with respect to the main portion, said lower rigid portion having 10 15 marginal longitudinal flanges and a transversely extending rib at the juncture between said lower rigid portion and said bowed portion, said parallel upper and lower rigid portions being provided with overlapping slots extending forwardly and rearwardly, substantially vertically disposed bolt means extending through said slots, and releasable means for securing said bolt means in adjusted position so that the bolt means may co-operate with the inner portion for establishing 20 25 and maintaining the effective position thereof for window sills of different dimensions.

12. A window seat comprising a main portion adapted to extend across the window sill and to support the body of the user, and an inner portion adapted to extend about the inner edge of the window sill, said inner portion having an intermediate flexible portion connected with said main portion so as to permit adjustment of the inner portion forwardly or rearwardly with respect to the main portion, and adjustable bolt 30 35 means extending between said main and inner portions for co-operation with said inner portion for establishing and maintaining the effective position thereof for window sills of different dimensions.

JOSEPH A. COSTELLO.
